(57) **CLAIM**

We claim the ornamental design for a bottle with cap, as shown and described.

DESCRIPTION

FIG. 1 is a front, right and top perspective view of a first embodiment of a bottle with cap showing our new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front, right and top perspective view of a second embodiment of a bottle with cap showing our new design;

FIG. 9 is a front elevational view of the bottle with cap of FIG.

8;

FIG. 10 is a back elevational view of the bottle with cap of FIG. 8;

FIG. 11 is a left side elevational view of the bottle with cap of FIG. 8;

FIG. 12 is a right side elevational view of the bottle with cap of FIG. 8;

FIG. 13 is a top plan view of the bottle with cap of FIG. 8;

FIG. 14 is a bottom plan view of the bottle with cap of FIG. 8;

FIG. 15 is a front, right and top perspective view of a third embodiment of a bottle with cap showing our new design;

FIG. 16 is a front elevational view of the bottle with cap of FIG. 15;

FIG. 17 is a back elevational view of the bottle with cap of FIG. 15;

FIG. 18 is a left side elevational view of the bottle with cap of FIG. 15;

FIG. 19 is a right side elevational view of the bottle with cap of FIG. 15;

FIG. 20 is a top plan view of the bottle with cap of FIG. 15; and,

FIG. 21 is a bottom plan view of the bottle with cap of FIG. 15.

The broken lines shown on the bottom surface in FIGS. 7, 14, & 21 are included for the purpose of illustrating environmental structure and form no part of the claimed design.

1 Claim, 12 Drawing Sheets
